United States Patent Office

Des. 229,498

Patented Dec. 4, 1973

229,498

TELEVISION ANTENNA

Harvey R. Brandt and Nicholas Werner, Somerville, N.J.,
assignors to Gavin Electronics Division, Antennacraft
Company

Filed Nov. 15, 1972, Ser. No. 306,799

Term of patent 14 years

Int. Cl. D14—03

U.S. Cl. D26—14 F

Fig. 3

FIG. 1 is a perspective view of a television antenna showing our new design;

FIG. 2 is one side view thereof;

FIG. 3 is a top plan view thereof;

FIG. 4 is a front view thereof;

FIG. 5 is a rear view thereof; and

FIG. 6 is the other side view thereof.

We claim:

The ornamental design for a television antenna, as shown and described.
